NONREFILLABLE DRUM

Charles Sabatt and Daniel F. Manion, Jr., Oil City, Pa., assignors to Rouseville Cooperage Company, Rouseville, Pa., a corporation of Pennsylvania

Application May 19, 1938, Serial No. 208,866

7 Claims. (Cl. 220—86)

This invention relates to improvements in drums for storing and transporting liquids such as lubricating oils, for example, and more particularly the invention is concerned with drums of the kind wherein provision is made for temporarily mounting a pump which is available for drawing off the contents as desired.

The principal object of the invention is to provide a drum which is so designed that unauthorized refilling is discouraged, this object contemplating a drum having a pump mounting which is rendered ineffective for further use when the pump which is employed to withdraw the original contents is once detached.

A further object is a drum in which provision is made for guarding against tampering with the pump mounting.

A still further object is to provide for facility in attaching and detaching the pump.

A still further object is to provide a drum which is simple in design and which may be manufactured economically.

The invention is illustrated in the accompanying drawing in which—

Figure 1 is a perspective view of a drum embodying the features of the invention;

Figure 2 is an enlarged broken section taken along lines 2—2 of Figure 1;

Figure 3 is a fragmentary view taken along line 3—3 of Figure 2;

Figure 4 is a fragmentary section taken along line 4—4 of Figure 3;

Figure 5 is a sectional view of a modified form of valve for admitting air to the drum; and

Figure 6 is an enlarged detail section taken along line 6—6 of Figure 3.

The drum, as illustrated, includes a head 6 which is formed with openings 7 and 8 (Figure 2), the metal surrounding said openings being extruded to provide necks 9 and 10, respectively. The opening 7 is closed by a cap 11 while the opening 8 is closed by a similar cap 12. The said caps carry sealing elements 13 which seat upon flanges 14 formed on the necks 9 and 10 and are preferably scored as indicated at 15 (Figure 3) in order to facilitate their removal. The opening 7 communicates with the interior of the drum through a tube 16, the upper end of which is suitably secured to the under side 0 of the head 6 and the lower end of which is formed with a port 17. A valve 18 cooperates with the said port. It is normally partially open and is, therefore, adapted to permit air to enter the drum or the contents to be drawn off when the cap 11 is removed. The said valve will

close, however, in the event that an attempt is made to refill the drum through the opening 7, an apertured plate 18a which is secured in the tube 16 preventing tampering with the valve.

The opening 8 is adapted to accommodate the barrel 19a of the pump which is employed to draw off the contents of the drum. In accordance with the invention an internally threaded element 20 is arranged under the opening 8 in a shallow depression 21 which is formed in the head 6 and is supported therein by diametrically opposed holders 22, a hard metal ring 20a preferably being secured in the depression between the top of the head and the said element. The holders 22, as illustrated, are secured by rivets 22a in end-for-end relation to the under side of the head 6 and are formed with arcuate, offset, resilient tongues 23 and depending tail-pieces 24. The outer ends of the tongues 23 are formed with openings 23a through which pins 23b extend. The latter are headed; they are carried by the head 6; and they permit free movement of the said tongues toward the head but prevent their movement in the opposite direction beyond the dotted line position indicated in Figures 2 and 5. The tongues 23 cooperate with arms 25 which are formed or provided upon the element 20 and preferably are inclined slightly toward the drum head, their off-setting providing shoulders 26 against which the said arms abut. Preferably a hard metal ring 23c is secured to the head 6 around the depression 21, the inside diameter of the said ring being substantially the same as that of the depression 21 while the outermarginal edge overlies the arms 25.

The element 20 is applied to the drum head by initially adjusting it so that the arms 25 are located in the spaces between the ends of the holders 22. It is then free to enter the depression 21. Thereafter the outer ends of the tongues 23 are sprung away from the drum head and the element rotated in a counter-clockwise direction to cause the arms 25 thereof to move behind the tongues into engagement with the shoulders 26, it being noted that the pins 23b are located just beyond the path of the arms 25 and hence do not interfere with the manipulation of the said element in the manner described. The element will be held in the position described by the frictional engagement between the arms 25 and the tongues 23.

The pump which is employed to draw off the contents of the drum is attached (after removal of the cap 12) by inserting the barrel 19a there-

of through the opening 8, the said barrel passing through the element 20 until a threaded section 29 thereof engages the threads in the element. When the parts are so adjusted a rotary movement 5 of the barrel 19a in a clockwise direction will cause the pump to be firmly secured upon the seat provided by the flange of the neck 10, rotation of the element 20 with the barrel being prevented by the engagement of the arms 25 with the shoulders 26. The contents of the drum 10 may, therefore, be drawn off as desired. When the drum has been emptied the pump may be removed by rotating the barrel 19a in a counter-clockwise direction. The element 20 turns with 15 the barrel 19a until it is arrested by the engagement of the arms 25 with the tail-pieces 24, as illustrated in dotted lines in Figure 3, the said arms forcing the tongues 23 aside and passing beyond their outer ends before engaging the tail-pieces. Continued rotation of the barrel 19a, therefore, unscrews the element 20, it being noted 20 that the tail-pieces 24 are of such a length that they hold the element against rotation while permitting it to move toward the lower end of the barrel as it is unscrewed. Upon disengagement 25 of the threads in the element with those on the barrel the element slides down the barrel and drops into the bottom of the drum.

A modified form of valve for venting the drum 30 is shown in Figure 5. In this embodiment an internally threaded plug 30 is secured in the opening 7. The said plug carries a threaded element 31 which has heads 31a and 31b and which is adjustable between the limits indicated 35 in dotted lines; it is formed with a central bore 32 which connects with a lateral passage 33; and it is adjustable to one position in which the head 31a seats against the plug to seal the opening 7 and it is adjustable to a second position 40 in which the head 31a is spaced from the end of said plug to permit air to enter the drum through the passage 33 and the bore 32.

From the foregoing it will be apparent that the pump can be attached to the drum only 45 once, its removal automatically dislocating the element 20 so that it is unavailable for further use. Not only is refilling of the drum thus discouraged but provision is made for guarding against tampering with the pump mounting, the 50 rings 20a and 23c cooperating to provide a shield which is hard enough to resist the action of a drill or similar tool. Unauthorized access to the element 20, after the pump is once attached, for the purpose of locking the said element so that 55 it cannot turn with the pump when the latter is removed is thus prevented. At the same time the pins 23b make it difficult to insert a tool through the opening 8 (after the pump has been removed and the element 20 has dropped into 60 the bottom of the drum) and bend the tongues 23 downwardly so that the element 20 may be manipulated in such a manner that it can be restored to its original operative position.

We claim as our invention:

65 1. Non-re-usable means for removably securing a dispensing pump to a container having an opening through which the barrel of the pump is adapted to be inserted, said means including an element which is located within said container 70 and means for supporting said element in such relation to said opening that it is engaged by a part on said barrel when the latter is inserted through said opening and moved in one direction, said last named means being operative to 75 release said element when said barrel is moved in

a second direction so that when it is disengaged from said part it will move to a position in said container in which it is rendered ineffective for further use.

2. Non-re-usable means for removably securing a dispensing pump to a container having an opening through which the barrel of the pump is adapted to be inserted, said means including an element which is located within said container and means for supporting said element 10 in such relation to said opening that it is engaged by a part on said barrel when this latter is inserted through said opening and rotated in one direction, said last named means being operative to release said element when said barrel 15 is rotated in the opposite direction so that when it is disengaged from said part it will move to a position in said container in which it is rendered ineffective for further use.

3. Non-re-usable means for removably securing a dispensing pump to a container having an opening through which the barrel of the pump is adapted to be inserted, said means including an internally threaded element which is located within said container and through which said barrel passes, said element engaging a threaded section on said barrel when the latter is rotated in one direction and being disengaged from said section when said barrel is rotated in the opposite direction, said element having radial arms 20 and holders which are secured to said container and which cooperate with said arms to support said element under and in substantially concentric relation with respect to said opening, said 25 holders supporting said element so that it is held against movement in said first named direction and being operative to permit said element to move a predetermined distance in said second mentioned direction when said pump is detached, whereby to release said arms and permit said 40 element to move to a position in which it is rendered ineffective for further use.

4. Non-re-usable means for removably securing a dispensing pump to a container having an opening through which the barrel of the pump 45 is adapted to be inserted, said means including an internally threaded element which is located within said container and through which said barrel passes, said element having radial arms and holders which are secured to said container, 50 said holders having resilient tongues which cooperate with said arms to support said element under and in substantially concentric relation with respect to said opening, said tongues yielding when said pump is detached to release said 55 arms and permit said element to move to a position in which it is rendered ineffective for further use.

5. Non-re-usable means for removably securing a dispensing pump to a container having an 60 opening through which the barrel of the pump is adapted to be inserted, said means including an internally threaded element which is located within said container and which may be screwed upon a threaded section on said barrel by rotating the barrel in one direction and unscrewed by rotating the barrel in the opposite direction, said element having radial arms and holders which are secured to said container, said holders being 65 formed to provide shoulders against which said arms abut to prevent rotation of said element when said barrel is rotated in said first named direction and having resilient tongues which 70 cooperate with said arms to support said element under and in substantially concentric relation 75

with respect to said opening, said arms moving said tongues aside when said barrel is rotated in said second named direction, whereby to release said element and permit it to move to a position in which it is rendered ineffective for further use.

6. Non-re-usable means for removably securing a dispensing pump to a container having an opening through which the barrel of the pump is adapted to be inserted, said means including an internally threaded element which is located within said container and which may be screwed upon a threaded section on said barrel by rotating the barrel in one direction and unscrewed by 10 rotating the barrel in the opposite direction, said element having radial arms, holders which are secured to said container, said holders being formed to provide shoulders against which said arms abut to prevent rotation of said element 15 when said barrel is rotated in said first named direction and having resilient tongues which cooperate with said arms to support said element under and in substantially concentric relation with respect to said opening, said arms moving said tongues aside when said barrel is rotated 20

in said second named direction and means for arresting the movement of said element after said arms have cleared said tongues, whereby to prevent said element from rotating further with said barrel.

7. Non-re-usable means for removably securing a dispensing pump to a container having an opening through which the barrel of the pump is adapted to be inserted, said means including an internally threaded element which is located 5 within said container and through which said barrel passes, said element having radial arms, holders which are secured to said container, said holders having resilient tongues which cooperate with said arms to support said element under 10 and in substantially concentric relation with respect to said opening, said tongues yielding when said pump is detached to release said arms and permit said element to move to a position in 15 which it is rendered ineffective for further use and means for limiting the yielding movement of said tongues.
